UNITED STATES PATENT OFFICE.

JOHN ERICSSON, OF NEW YORK, N. Y., ASSIGNOR OF ONE-HALF TO CORNELIUS H. DELAMATER AND GEORGE H. ROBINSON, BOTH OF SAME PLACE.

MARINE TORPEDO.

SPECIFICATION forming part of Letters Patent No. 245,804, dated August 16, 1881.
Application filed May 28, 1881. (No model.) Patented in England December 21, 1880.

To all whom it may concern:

Be it known that I, JOHN ERICSSON, of the city, county, and State of New York, have invented a new and useful Improvement in Explosive Projectiles, of which the following is a specification, reference being had to the accompanying drawings.

This improvement relates to that class of explosive projectiles known as submarine torpedoes to be projected from guns placed under water or below the water-lines of the vessels which carry them.

It consists in a novel construction of a projectile of this class having a wooden body and tail, whereby such body and tail are made capable of resisting the tendency to crush them lengthwise consequent upon the force applied to project the projectile from a gun.

Figure 1 in the drawings is a central longitudinal section of a torpedo constructed according to my invention. Fig. 2 is a rear end view of the same. Fig. 3 is a transverse section of the same on a larger scale in the line x x of Fig. 1.

The form of the projectile represented is cylindrical at and near its center of displacement and conical in front and rear thereof, the conical profile of the front part or head, B, presenting a greater, and the conical profile of the rear part or tail, C, a lesser, angle to the axis, thereby providing for a capacious powder-chamber in the head for the exploding charge, and producing an elongated tail. On the tail are four radial and longitudinal steadyng wings or fins, F F. The center of displacement is intended to be forward of the middle of its length, and the weight of the projectile when charged and ready for use should be nearly equal to, but not greater than, the volume of water which it displaces.

The cylindrical portion A of the body is made of a solid piece of wood, with a ring or band, f, of iron firmly secured to its rear by screws i i. The tail-piece C is also made of wood, and is solid except that it is bored centrally for the reception of an iron rod, g, which

fits it tightly and runs through its entire length with a head at its rear end. The front of the tail-piece has firmly secured to it by screws j j a socket or flanged abutment-piece, h, which receives the rear portion—the ring f—and is secured thereto by screws k k, as best shown in Fig. 3. The rod g abuts against the plate forming the front of the socket h, and it is secured in the wood by iron pins l l, inserted transversely through the wood of the tail-piece and entering holes in the rod, as best shown in Fig. 1. The fins F F are also represented of wood having the edges faced with plates of iron or steel. The powder-chamber B fits over the front of the wooden body A, and is secured thereto by screws l l.

The firing device or percussion-fuse S, which is provided in the head of the projectile for firing the exploding charge, may be of any suitable construction; but I prefer to use a firing device such as is the subject-matter of my application for patent filed June 18, 1881.

The within-described construction of the wooden tail-piece with the central rod of iron and the connection of the tail-piece with the wooden body by the iron abutment-piece, against which the said central rod abuts, gives the wooden body and tail-piece all the strength and support necessary to enable them to resist the impact of the explosive force of the charge of powder employed to discharge the projectile from a gun.

What I claim as my invention, and desire to secure by Letters Patent, is—

The combination, in a projectile having a cylindrical body and conical tail-piece of wood, of an iron abutment-piece connecting the said body and tail-piece and a central rod of iron abutting against said abutment-piece and extending to the rear of the tail-piece, substantially as specified.

J. ERICSSON.
